UNITED STATES PATENT OFFICE.

AUGUST O. TANNENBERG, OF OAKLAND, CALIFORNIA.

COMBINATION STEP-LADDER.

1,078,072.

Specification of Letters Patent.

Patented Nov. 11, 1913.

Application filed October 25, 1911. Serial No. 656,705.

To all whom it may concern:

Be it known that I, AUGUST O. TANNENBERG, a citizen of the United States, residing at 1108 Thirty-sixth avenue, Oakland, in the county of Alameda and State of California, have invented a new and useful Combination Step-Ladder, of which the following is a specification in such full and clear terms as will enable those skilled in the art 10 to construct and use the same.

This invention relates to an extension step-ladder and its object is to produce a step-ladder, which will be capable of use as an extension ladder and in other ways as will 15 be explained herein.

Another object of the invention is to produce an extension step-ladder which can be manufactured at less cost and which will be more reliable and more easily operated, than 20 most extension step ladders now in use.

A further object of the invention is to produce an extension step ladder which may be used on stair-ways or in other places where it may be necessary to have the foot of one 25 pair of legs placed in a different plane from the foot of the other pair of legs, as for example, the foot of one pair of legs is placed on the floor and the foot of the other pair of legs is placed upon a flight of stairs.

30 In the drawings in which the same numeral of reference is applied to the same portion throughout the several views, Figure 1 is a side elevation of the ladder in use as a step ladder. Fig. 2 is a side elevation of the ladder in use upon a stair way, this ladder being specially adapted for use in papering and tinting hall ways, where it is necessary to reach to the ceiling above the steps. Fig. 3 is a side elevation of the ladder in use as an extension ladder. Fig. 4 is a plan view of the ladder when in position as shown in Fig. 1. Fig. 5 is a horizontal section through the ladder on the line X-X. Fig. 6 is a plan view of the bracket used to 35 secure the two parts of the ladder together. Fig. 7 is a perspective view of the side brackets at the top of the ladder.

The numeral 1 represents the side rails of the front part of the ladder, steps 2 connecting the side rails, a wide step 3 being placed at the top of the rails 1. At the top of the two rails on the side thereof is a backwardly extending bracket 4, said bracket having a notch 6 therein, a slot 7 and a curved pocket 8 at the bottom of slot 7.

The back portion of the ladder is made of

rails 5, connected by means of rungs 9. This portion of the ladder has a plate 10 secured at the top of the rails 5, said plate having lugs 11 and 12 thereon. The brackets 4 are 60 secured together by means of a bolt 22. Said brackets are also provided with two grooves, 13 and 14, said grooves being adapted to allow the passage of small channel-irons 15, which are secured to the side of each rail 5. 65 On each rail 1 there is a clamp 16, which clamp has its end 17 far enough away from the rail 1 to pass over the channel iron 15, as indicated in Fig. 3, to hold the two parts of the ladder in the position indicated in 70 Fig. 3. Pivoted on the inside of each rail 1 is a hook 18, the two hooks being connected by means of a bar 19. These two hooks hold the two parts of the ladder in any desired extension, as is indicated in Fig. 3. 75

In use the ladder may be swung to the position in Fig. 1. The lug 11 will move into the pocket at the bottom of the slot 6 and the lug 12 will move into the pocket 8 at the bottom of the slot 7, thus determining 80 the amount of spread of the two parts of the ladder. When it is desired to use the ladder on a stair-way, as indicated in Fig. 2, the rear ladder rails 5 are brought up to the rails 1 and the lugs 11 and 12 are lifted 85 out of the slots 6 and 7, whereupon the ladder may be shifted to the position shown in Fig. 2, the square end 20 of the bracket 4 bearing in any of the notches 30 in the edge of the rails 5, to prevent the two parts 90 of the ladder changing their relative position, after having once been set as indicated. When in this position the channel irons 15 slide into grooves 14 on the inside of brackets 4, if it is desired to move the ladder 5 95 still higher than is shown in Fig. 2. Should it be desired to use the ladder as an extension ladder, the rails may be moved as indicated in Fig. 3, any one of the rungs thereof being placed above the hook members 18. 100 When in this position the channel irons 15 are held by means of the groove 13 and clamp 16, thus making the ladder substantially as rigid as if made in one part.

It will be clear from the number of adjustments provided upon this ladder that it has a wide field for use.

In order to insure holding the two parts of the ladder in their relative position, the rails 5 are provided with a number of 110 notches 30, as shown in Fig. 2. The notches 30 in the stile 1 take against the corner of

the upper end of the stile members 1, the brackets 4 being in contact with the outside of the stiles 1 and 5.

While the ladder shown illustrates a comparatively short ladder, it will be clear that the length thereof may be varied to suit conditions. It will also be clear that when the ladder 5 and ladder 1 are in their most extended positions, that is, when the bottom of the ladder 5 is up close to the top of the ladder 1, either as shown in Fig. 2, or as shown in Fig. 5, that it is necessary for the rails 15 to engage the inside of the grooves 13 or 14 as the case may be in order to give the two parts of the ladder the necessary rigidity.

Having thus described my invention what I claim as new and desire to secure by Letters Patent of the United States, is as follows:

1. In a step ladder, two ladder members, each having a set of steps, two oppositely placed slotted brackets secured at the top of one member, two oppositely placed plates each having two lugs thereon which coöperate with the two slotted brackets to prevent the two ladder members from separating more than a given angle, the lugs being removable from said brackets when the two ladder members are substantially parallel with each other, as described.

2. In a step ladder, two ladder members each having a series of steps, two oppositely placed slotted brackets secured at the top of one of said members, lugs at the top of the other member, a guide on each side of one of said members, said guides being adapted to pass through said brackets at two different angles, and means to hold the two ladder members in several different heights relative to each other, as described.

3. In a step ladder, two ladder members each having a series of steps, two oppositely

placed slotted brackets at the top of one of said members, two oppositely placed plates each having lugs thereon at the top of the other ladder member, guides on the side of the second member, means to hold said members in any desired longitudinal adjustment when lying in substantially the same plane, and means whereby the two members may be secured in a plurality of adjustments when lying at an acute angle to each other, as described.

4. In a step ladder, two ladder members each having a set of steps, oppositely placed slotted brackets secured at the top of one of said members, oppositely placed plates secured at the top of the other member, lugs on the latter plates to hinge the second member to the brackets secured to the first member, and to prevent the two members from being separated more than a given angle, the second member having notches to permit the two ladder members to be placed in varying relative longitudinal adjustments when lying at an acute angle to each other, as described.

5. In a step ladder, two ladder members, brackets secured at the top of one member, plates secured at the top of the other member, lugs carried by said plates to hinge the two members together, the second members having notches whereby the two members may be secured in a number of different adjustments when the lugs are disengaged and the two ladder members are lying at an acute angle to each other, as described.

In testimony whereof I have hereunto set my hand this 7th day of October A. D. 1911, in the presence of the two subscribed witnesses.

AUGUST O. TANNENBERG.
